UNITED STATES PATENT OFFICE

123,843

DESIGN FOR A CHRISTMAS TREE ORNAMENT

Joseph Reich, New York, N. Y.

Application August 27, 1940, Serial No. 94,647

Term of patent 7 years

To all whom it may concern:

Be it known that I, Joseph Reich, a citizen of Hungary, residing at New York city, in the county of New York and State of New York, have invented a new, original, and ornamental Design for a Christmas Tree Ornament, of which the following is a specification, reference being had to the accompanying drawing, forming a part thereof.

In the drawing,

Fig. 1 is a front elevational view of a Christmas tree ornament, showing my new design; Fig. 2 is a side elevational view thereof; and Fig. 3 is a rear view.

I claim:

The ornamental design for a Christmas tree ornament, as shown.

JOSEPH REICH.
